(57) **CLAIM**

The ornamental design for a phone with a graphical user interface, as shown and described.

DESCRIPTION

FIG. 1 is a front view of a phone with a graphical user interface showing a first image in the sequence showing our new design;

FIG. 2 is a bottom view thereof;

FIG. 3 is a top view thereof;

FIG. 4 is a right view thereof;

FIG. 5 is a rear view thereof;

FIG. 6 is a left view thereof;

FIG. 7 is a second image thereof;

FIG. 8 is a third image thereof;

FIG. 9 is a fourth image thereof;

FIG. 10 is a fifth image thereof;

FIG. 11 is a sixth image thereof;

FIG. 12 is a seventh image thereof;

FIG. 13 is an eighth image thereof;

FIG. 14 is a ninth image thereof;

FIG. 15 is a tenth image thereof;

FIG. 16 is an eleventh image thereof;

FIG. 17 is a twelfth image thereof;

FIG. 18 is a thirteenth image thereof;

FIG. 19 is a fourteenth image thereof;

FIG. 20 is a fifteenth image thereof;

FIG. 21 is a sixteenth image thereof;

FIG. 22 is a seventeenth image thereof;

FIG. 23 is an eighteenth image thereof;

FIG. 24 is a nineteenth image thereof;

FIG. 25 is a twentieth image thereof;

FIG. 26 is a twenty-first image thereof;

FIG. 27 is a twenty-second image thereof;

FIG. 28 is a twenty-third image thereof;

FIG. 29 is a twenty-fourth image thereof;

FIG. 30 is a twenty-fifth image thereof;

FIG. 31 is a twenty-sixth image thereof;

FIG. 32 is a twenty-seventh image thereof;

FIG. 33 is a twenty-eighth image thereof;

FIG. 34 is a twenty-ninth image thereof; and,

FIG. 35 is a thirtieth image thereof.

The broken lines around and within the drawings show a boundary and contour of a phone, and forms no part of the claimed design.

(Continued)

The appearance of the images transitions between the images shown in FIGS. 1, 7 through 35. The process or period in which one image transitions to another forms no part of the claimed design.

1 Claim, 35 Drawing Sheets
